United States Patent Office

Des. 203,905
Patented Feb. 22, 1966

203,905

DISPLAY STAND FOR CONFECTIONES OR THE LIKE

Robert L. Dixon, 12 Brompton Road, Garden City, N.Y.

Filed Mar. 23, 1964, Ser. No. 79,124

Term of patent 14 years

(Cl. D80—10)

FIG.1

FIG. 3

FIG. 1 is a front perspective view of a display stand for confections or the like embodying my new design, FIG. 2 is a side elevational view thereof, and

FIG. 3 is a rear elevational view thereof.

I claim:

The ornamental design for a display stand for confections or the like, as shown.
